Primary Examiner—James M. Gandy*Assistant Examiner*—Melody Brown*Attorney, Agent, or Firm*—Terry M. Gernstein**[57] CLAIM**

The ornamental design for a steering wheel, as shown and described.

DESCRIPTION

FIG. 1 is a perspective view of a steering wheel showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a bottom elevational view thereof;

FIG. 7 is a top plan view thereof; and,

FIG. 8 is a perspective view thereof, it being understood that the broken lines are for illustrative purposes only and form no part of the claimed design.

FIG. 8

FIG. 1

FIG. 2

FIG. 7

FIG. 3

FIG. 6

FIG. 5

FIG. 4
